UNITED STATES PATENT OFFICE.

WILDER P. RIX, OF KALAMAZOO, MICHIGAN.

WATER-CLOSET.

SPECIFICATION forming part of Letters Patent No. 792,730, dated June 20, 1905.

Application filed September 8, 1903. Serial No. 172,335.

To all whom it may concern:

Be it known that I, WILDER P. RIX, a citizen of the United States, residing at the city of Kalamazoo, in the county of Kalamazoo and 5 State of Michigan, have invented certain new and useful Improvements in Water-Closets, of which the following is a specification.

This invention relates to improvements in water-closets.

10 The objects of this invention are, first, to provide an improved water-closet adapted to prevent the escape of odors therefrom into the room; second, to provide an improved water-closet which aids in ventilating the room in 15 which it is located; third, to provide an improved self-ventilating water-closet which is simple and compact in structure, economical to produce, and not likely to get out of repair.

Further objects and objects relating to structural details will definitely appear from the 20 detailed description to follow.

I accomplish the objects of my invention by the devices and means described in the following specification.

25 The invention is clearly defined and pointed out in the claims.

A structure embodying the features of my invention is fully illustrated in the accompanying drawings, forming a part of this specification, in which—

Figure 1 is a front elevation view of a structure embodying the features of my invention, the seat being illustrated in its open position to show the arrangement of parts. Fig. 2 is 35 a detail sectional view taken on a line corresponding to line 2 2 of Fig. 1 looking in the direction of the little arrows at the ends of the section-lines, the seat being shown in its closed position. Fig. 3 is a detail side elevation view of a modified construction, the seat only being shown and its movement indicated by dotted lines.

In the drawings similar letters of reference refer to similar parts throughout the several 45 views.

Referring to the drawings, the bowl A is provided with the usual or any desired flushing connections, the same not being here illustrated. The seat B is suitably hinged to the 50 hinge-plate B'. The lid or cover C is also se-

cured in position by suitable hinges in the usual or any desired manner.

On the under side of the seat B is a gasket b, adapted to rest on the top of the bowl when the seat is in its closed position, making a tight 55 gas-joint between the seat and the bowl.

An annular chamber or ventilator D, having perforations or ports d therein and adapted to form a ventilator therefor, is secured to the seat B. A delivery-passage E is provided 60 for the chamber or ventilator. This passage E is adapted to register with the passage E' when the seat is in its closed position. These passages E and E' are preferably formed within the body of the seat B and the hinge-plate 65 B', respectively. The passage E' is connected to a suitable ventilating-pipe in the wall or to the chimney.

A draft-pipe F, preferably cast in the side of the bowl, as appears in Fig. 1, is provided. 70 The lower end of this pipe opens near the floor and the upper end is connected to the ventilator by the hollow arm D' thereon, the opening of which registers with the upper open end of the draft-pipe F when the seat is in its 75 closed position. By this arrangement a draft is produced and the odors and noxious gases in the bowl are collected and carried away by the ventilator.

With the lower end of the draft-pipe F arranged near the floor the foul air is drawn 80 into the pipe and the room ventilated thereby.

The draft-pipe F may be omitted and valuable results still be secured both in carrying off the odors from the bowl and in ventilating 85 the room.

As the gasket b forms a tight joint between the seat and the bowl, the bowl is practically sealed when the lid is closed.

The casing or ventilator D being connected 90 to a suitable ventilating-pipe or to the chimney a very strong draft is secured, so that practically none of the gases or odors from the bowl escape into the room, and, as before remarked, the room is also ventilated thereby. 95

In the modified structure shown in Fig. 3 the draft-pipe F is secured to the ventilator D instead of being cast in the bowl. The draft-pipe F is pivotally secured to the ventilator, so that it takes the position indicated 100

by dotted lines (see Fig. 3) when the seat B is open. This modified construction is particularly desirable, as it is applicable to bowls now in general use.

5 I have illustrated and described my improved water-closet in the form preferred by me on account of its neat appearance and its economy of production. I am aware, however, that it is capable of very great variations in structural details without departing from my invention.

Having thus described my invention, what I claim as new, and desire to secure by Letters Patent, is—

15 1. In a water-closet, the combination of a bowl; a seat; a gasket b secured to said seat; a suitable lid or cover for said seat; an annular chamber having a plurality of ports therein, adapted to fit within the rim of said bowl 20 when said seat is in its closed position, secured to said seat; a delivery-passage for said chamber formed within the body of said seat; a hinge-plate for said seat having a passage therein, adapted to be connected to a suitable 25 ventilator-pipe and adapted to connect with said delivery-passage for said chamber when the said seat is in its closed position; and a draft-pipe formed in said bowl, arranged to deliver into said chamber when said seat is in its closed position, for 30 its closed position, for the purpose specified.

2. In a water-closet, the combination of a bowl; a seat; a suitable lid or cover for said seat; an annular chamber having a plurality of ports therein, adapted to fit within the 35 rim of said bowl when said seat is in its closed position, secured to said seat; a delivery-passage for said chamber formed within the body of said seat; a hinge-plate for said seat hav-

ing a passage therein, adapted to be connected to a suitable ventilator-pipe and adapted 40 to connect with said delivery-passage for said chamber when the said seat is in its closed position; and a draft-pipe formed in said bowl arranged to deliver into said chamber when the seat is in its closed position, for the purpose specified. 45

3. In a water-closet, the combination of a bowl; a seat; an annular chamber having a plurality of ports therein, adapted to fit within the rim of said bowl when said seat is in its closed position, secured to said seat; a delivery-passage for said chamber formed within 50 the body of said seat; a hinge-plate for said seat having a passage therein, adapted to be connected to a suitable ventilator-pipe and 55 adapted to connect with said delivery-passage for said chamber when said seat is in its closed position; and a draft-pipe formed in said bowl arranged to deliver into said chamber when the seat is in its closed position, for 60 the purpose specified.

4. The combination of a bowl; a seat; an annular chamber having a plurality of ports therein, adapted to fit within the rim of said bowl, when said seat is in its closed position, 65 secured to said seat; a delivery-passage for said chamber; and a draft-pipe formed in said bowl arranged to deliver into said chamber when the said seat is in its closed position, for 70 the purpose specified.

In witness whereof I have hereunto set my hand and seal in the presence of two witnesses.

WILDER P. RIX. [L. s.]
